Atty.

UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTROPNEUMATIC BRAKE.

1,251,596.

Specification of Letters Patent.

Patented Jan. 1, 1918.

Application filed December 6, 1916. Serial No. 135,365.

To all whom it may concern:

Be it known that I, WALTER V. TURNER, a citizen of the United States, residing at Wilkinsburg, in the county of Allegheny and State of Pennsylvania, have invented new and useful Improvements in Electro-pneumatic Brakes, of which the following is a specification.

This invention relates to electro-pneumatic brakes, and more particularly to an equipment employing pneumatically independent units on each vehicle adapted to be controlled wholly by electrical means.

One object of my invention is to provide electrically controlled means for effecting an emergency application of the brakes and adapted to control the exhaust from the brake cylinder, so that in case of failure of the release circuit, the emergency brake will not be lost.

Another object of my invention is to provide an electrically controlled device for effecting an emergency application of the brakes upon deenergization and adapted to be energized from the release circuit under certain conditions, so that in case of failure of the release circuit, an emergency application of the brakes will be effected.

Other objects and advantages will appear in the following more detailed description of the invention.

In the accompanying drawing, Figure 1 is a diagrammatic view of an electro-pneumatic brake equipment embodying my invention, and Fig. 2 a diagram illustrating the electric connections which are effected in the various positions of the brake controlling switch device.

According to a preferred form of my invention, a main casting 1 may be provided, to which is applied a service magnet 2 for controlling a service valve 3, a release magnet 4, adapted to control a release valve 5, and an emergency magnet 6 for controlling a double beat valve 7.

A supply reservoir 8, which may be the main reservoir, is connected by a pipe 9 to a passage 10 which leads to the chamber at one side of the double beat emergency valve 7 and to the chamber at one side of service valve 3.

The brake cylinder 11 is connected by pipe 12 to a passage 13 leading to the chamber at the opposite side of the service valve

3 and to the chamber at one side of release valve 5.

One terminal of the service magnet 2 is connected to a service train wire 14, one terminal of the release magnet 4 to the return release wire 15 and one terminal of the emergency magnet 6 to emergency wire 16, the other terminals of said magnets being connected to the common negative battery wire 17.

A positive battery wire 18 is connected through a source of current 19 with the negative battery wire 17 and at the end of the train is connected to a supply train wire 20, the return release wire 15 being also connected at the end of the train with a release wire 21.

An electric brake switch 22 is provided at each end of the car and has a contact 23 and a three point contact 24 adapted for engagement with contact fingers connected to the corresponding train wires.

The brake switch at the left of the drawing is shown in handle off position, in which no operating connections are made. In release position of the brake switch, as shown at the right of the drawing, the contact 23 connects the supply wire 20 with the emergency wire 16, so that the emergency magnet is energized by current supplied from the source of current 19 through wire 18, jumper connection at end of train, wire 20, contact 23 in brake switch, wire 16, to emergency magnet 6 and thence to negative battery wire 17. In this position, the service and release magnets are deenergized, closing service valve 3 and opening release valve 5. The energization of the emergency magnet 6 causes the double beat valve 7 to seat at its lower seat and consequently, the brake cylinder 11 is open to the exhaust through passage 13, past release valve 5 to a passage 25, leading to the valve chamber of the double beat valve 7 and thence to exhaust port 26.

If it is desired to effect a service application of the brakes, the brake switch is turned to service position, in which contact 24 connects the service wire 14 and the emergency wire 16 with the return release wire 15, and the contact 23 connects the release wire 21 with the supply wire 20, and consequently, since the return release wire 15 is connected to the release wire 21 at the

rear end of the train, both the service magnet 2 and the emergency magnet 6 will be energized, as well as the release magnet 4.

The energization of release magnet 4 closes the release valve 5 and prevents the exhaust of fluid from the brake cylinder and the energization of service magnet 2 opens the service valve 3, so that fluid is supplied from supply reservoir 8 through passage 10 past valve 3 to passage 13 and thence to brake cylinder 11.

When the desired brake cylinder pressure is attained, the brake switch may be turned to lap position, in which the release wire 21 is still connected to supply wire 20 by contact 23, so that the release magnet 4 remains energized and fluid is retained in the brake cylinder. The circuit of the service magnet 2, however, is opened, so that the service magnet is deenergized, and the service valve 3 shifted to closed position, thus preventing the further admission of fluid to the brake cylinder. The emergency wire 16 is still connected to the return release wire 15, so that the emergency magnet remains energized.

If it is desired to release the brakes, the brake switch is turned to release position, in which, as hereinbefore described, the service and release magnets are deenergized while the emergency magnet is energized, so that fluid is released from the brake cylinder.

An emergency application of the brakes may be manually effected by turning the brake switch to emergency position, in which all of the circuits are opened, and the magnets are deenergized, thereby closing the service valve 3, the release valve 4, and causing the double beat valve 7 to assume its upper seat, in which the exhaust port 26 is cut off from the brake cylinder and communication is opened from reservoir 8 through passage 10 past valve 7 to passage 25 which leads to passage 13 past a check valve 27.

In case of a train break-in-two, since the emergency wire receives current from the supply wire through the connection at the rear end of the train, the breaking of the supply wire at any point will cause the deenergization of all the emergency magnets, so as to effect an emergency application of the brakes throughout the train.

Fig. 2 of the drawings shows the connections made in the different positions of the brake switch, but does not correspond structurally with the brake switch, since as shown in Fig. 1, in the actual construction, the contact fingers are arranged in a horizontal plane, while for convenience in illustrating the different positions, the contact fingers in Fig. 2 are arranged in a vertical plane.

The exhaust from the brake cylinder is controlled by the emergency magnet valve, so that in case the emergency magnet is

deenergized from any cause, the brake cylinder exhaust will be closed and fluid supplied to the brake cylinder by the emergency valve will be retained, regardless of whether or not the release magnet is energized or de- 70 energized.

In service and lap positions, the release magnet is energized to hold the release valve 5 closed. If the release circuit is broken at any point, the release valve will open. In 75 order to prevent loss of the brake under the above condition, the emergency magnet wire 16 is connected in service and lap positions with the return release wire, so that should the release circuit be broken, the circuit of 80 the emergency magnets will also be opened, and the emergency magnets thereby deenergized to effect an emergency application of the brakes.

Having now described my invention, what 85 I claim as new and desire to secure by Letters Patent is:—

1. In an electro-pneumatic brake, the combination with a brake cylinder, of an emergency magnet valve for effecting an emergency application of the brakes and adapted to control the exhaust from the brake cylinder. 90
2. In an electro-pneumatic brake, the combination with a brake cylinder, of an emergency magnet valve for effecting an emergency application of the brakes and for controlling the brake cylinder exhaust and a release magnet valve for controlling communication from the brake cylinder through 100 said exhaust.
3. In an electro-pneumatic brake, the combination with a release magnet and valve, of a normally energized emergency magnet and valve adapted to be energized through the 105 circuit of the release magnet.
4. In an electro-pneumatic brake, the combination with a brake cylinder, a valve for controlling the release of fluid from the brake cylinder, and a normally deenergized magnet for controlling said valve, of an emergency valve for controlling the admission of fluid to the brake cylinder and a magnet energized through the circuit of the release magnet for controlling the emergency 115 valve.

5. In an electro-pneumatic brake, the combination with a magnet for controlling the release of the brakes and adapted upon energization to close the release, of a normally 120 energized emergency magnet and means for connecting said magnet to the release circuit when the release circuit is energized, to thereby cause an emergency application of the brakes upon failure of the release circuit. 125

6. In an electro-pneumatic brake, the combination with a service magnet and valve for effecting a service application of the brakes and a release magnet and valve for closing the brake cylinder exhaust upon 130

energization of the release magnet in making a service application of the brakes, of a normally energized emergency magnet adapted to be energized through said release circuit in a service application of the brakes.

7. In an electro-pneumatic brake, the combination with electrically controlled means for effecting a service application and the release of the brakes, of electrically controlled means adapted upon deenergization to effect an emergency application of the brakes and means for energizing said electrically controlled emergency means from the release circuit in making a service application of the brakes.

8. In an electro-pneumatic brake, the combination with a magnet valve device for effecting a service application of the brakes, a magnet valve device for effecting the release of the brakes, and a magnet valve device for effecting an emergency application of the brakes, of a brake switch device having a service application and a lap position in which the emergency magnet valve device is energized from the release circuit of the release magnet valve device.

In testimony whereof I hereunto set my hand.

WALTER V. TURNER.
